INFLATABLE FLOTATION DEVICE

Daniel Mapes, Upper Montclair, N. J., assignor to
Walter Kidde & Company, Inc., Bloomfield,
N. J., a corporation of New York

Original application April 8, 1933, Serial No.
665,090. Divided and this application Febru-
ary 19, 1934, Serial No. 711,838

2 Claims. (Cl. 221—73.5)

The present invention is a division of applicant's copending application Serial No. 665,090, filed April 8, 1933, for "Inflatable flotation devices", and embodies that portion of said application which relates to inflatable flotation devices, such as life-vests or belts, for individual use.

More specifically the invention relates to inflatable flotation devices of the type comprising a plurality of individual compartments inflated by air or other gas, for example, carbon dioxide stored under pressure.

Inflatable flotation devices of the type in use prior to the present invention and of the construction embodying a plurality of inflatable compartments, have either been provided with individual compartments supplied by separate sources of inflating medium or have been provided with intercommunicating compartments supplied from a single source of inflating medium.

The disadvantages of the first type of construction are at once apparent since the compartments, being individually inflatable, can not be arranged for simultaneous release of the separate sources of inflating medium without more or less complicated control apparatus; and since the duplication of the sources of inflating medium is both cumbersome and uneconomical.

With reference to the second type of construction, having intercommunicating compartments supplied from a single source of inflating medium, wherein the admission of inflating medium to one compartment will cause the medium to flow to all the compartments, the undesirable feature is that, in the event of an accident causing puncturing and deflation of one compartment, the remaining compartments will be immediately deflated, thus rendering the flotation device useless.

It is accordingly an object of this invention to provide an inflatable flotation device, such as a life-vest or belt, or the like, having a plurality of inflatable compartments which are not in intercommunication but which are nevertheless adapted for simultaneous inflation.

It is a further object of the invention to provide a flotation device of the type mentioned in which each of the separate compartments may be simultaneously inflated by pressure medium from a single pressure medium storage container.

It is a still further object of the present invention to provide a pressure medium distributing manifold arranged to receive pressure medium from a source thereof and distribute it to a plurality of compartments and also arranged to

prevent both reverse flow of the pressure medium from the compartment to the manifold and flow between the compartments.

It is also an object of the invention to provide a structural embodiment thereof which is particularly adapted for use with life-vests or life-belts.

These and other objects of the invention not specifically enumerated above will be apparent as the invention is described in greater detail in conjunction with the accompanying drawings, wherein:

Figure 1 is a view in elevation of a life-vest embodying the present invention, and showing the manner of assembly of the pressure medium container and the distributing manifold.

Figure 2 is a somewhat enlarged view, partially in section, showing the pressure medium container and certain features of construction of a distributing manifold in accordance with the invention.

Figure 3 is a still further enlarged cross-sectional view taken at right angles to Figure 2, and showing the pressure medium container and other features of construction of the distributing manifold of Figure 2.

Referring first to Figure 1, the reference numeral 1 represents a complete inflatable life-vest ready for use. Of course, the invention may be adapted to any form of life-preserved, but the description here is concerned with the construction in the form of a life-vest. Still referring to Figure 1, the vest is constructed with two or more individually but simultaneously inflatable compartments 2, 3, the compartments being preferably symmetrically arranged to encircle the wearer's neck, so that there will always be an equal buoyant effect on either side of the wearer regardless of the number of compartments inflated or the degree of inflation.

At 4 is shown a pressure medium storage container suitably secured to the vest structure and connected by means of a coupling member 5 to a distributing manifold 6 which in turn is connected by fittings 7 and 8 and branch connections 9 and 10 with the inflatable compartments 2 and 3, respectively.

In Figure 3, the pressure medium release means is shown comprising the coupling member 5, which is secured within the mouth of the container 4, the coupling member being provided with a passage 11 communicating at one end with the interior of the container and normally closed at the other end by a frangible disc 12 and sealing gasket 55

13 carried by a thimble 14 and held against a seat at the end of the passage 11 through the medium of a screw-threaded engagement of the thimble 14 with the coupling member 5. For the purpose 5 of releasing the pressure medium from the container, disc rupturing means is provided in the form of a cutter 15 provided with a bore 16 extending entirely therethrough. The cutter 15 is normally maintained out of contact with the frangible disc 12 by means of a coil spring 17 bearing at one end in a recess 18 in the thimble 14 and at the other end on a head 19 of the cutter 15, outward movement of the cutter being limited by a washer 20 secured against an internal shoulder 10 of the coupling 15 by means of a ring-shaped member 21 having a screw-threaded engagement with the coupling member 5. A thin disc 22 of some easily fracturable material, such as bakelite, is secured between the washer 20 and the ring-shaped member 21, the purpose of the disc 22 being to protect the cutter 15 against the corrosive effect of external media and against the intrusion of foreign matter which might tend to clog the passage 16. In order to control the flow of the 25 pressure medium from the container 4, passage 16 in the cutter is made of a predetermined size, and the cutter 15 itself is arranged for a close-working fit on its external surface with the bore 23 in the thimble 14. The means for actuating the cutter 15 to cause it to rupture the frangible disc and to permit the escape of the pressure medium will be described in connection with the assembly of the distributing manifold 6, in which this means is mounted.

30 As shown in Figures 2 and 3, the distributing manifold 6 comprises both means for distributing the pressure medium to the inflatable compartments of the vest and means for actuating the pressure medium release means. The latter means 35 40 comprises a pointed striking pin 24 guided within a bore 25 of a member 26, which is threaded within the end of the manifold which is secured to the coupling member 5 by the interengaging screw threads. The striking pin 24 is provided with a 45 head 27 adapted to be engaged by a cam member 28 secured on one end of a shaft 29 which is journaled within cooperating bushings 30 and 31, of which the bushing 30 passes through a wall of the distributing manifold 6. Packing 32 held between 50 the bushings 30 and 31 prevents leakage of the pressure medium past the shaft 29. Secured to the outer end of the shaft 29 is a lever 33 provided with an operating pull 34. The cam member 28 is normally maintained in its non-operated position 55 by engagement with a groove 35 of the cam member of a catch button 36 guided within a recessed extension 37 of the manifold and maintained in contact with the cam member by means of a coil spring 38. With the construction as thus 60 described, when the pull handle 34 is operated, the cam member 28 rotates against the yielding engagement of the catch button 36 and engages the head 27 of the striking pin 24, thus driving the striking pin through the fracturable disc 22 into engagement with the head 19 of the cutter 15, whereby the cutter is driven through the frangible disc 12, opening a passage for the pressure medium from the container 4 through the passages 11, 23 and 16, through openings 39 in the member 26 to the receiving chamber 40 of the distributing manifold, whence the medium discharges into the inflatable compartments 2 and 3 of the vest through the branch connections 9 and 10 and the fittings 7 and 8, the flow of the

pressure medium continuing until the pressure throughout the system has been equalized, at which time the compartments 2 and 3 are isolated from the receiving chamber 40 by the closing of the check valves 41, located in the branch connections 9 and 10. The construction of the check valves 41 is not shown in detail, as, in the present instance, they are ordinary commercial pneumatic tire air valves; and it is sufficient to know that the check valves permit flow of the pressure medium to the inflatable compartments, but prevent a reverse flow of the pressure medium from the inflatable compartments to the receiving chamber, at the same time preventing intercommunication of the inflatable compartments, which, in the event of the puncturing and deflation of one of the compartments, would cause deflation of the remaining compartment.

Referring again to Figure 1, the reference numerals 42 and 43 represent tubes connected to the inflatable compartments 2 and 3 through connections 44 and 45, through which tubes the inflation of the compartments of the vest may be maintained despite leakage of the inflating medium from the compartments. For this purpose the 20 ends of the tubes 43 and 44 are arranged near the neck-piece of the vest, so that they may easily be inserted in the mouth of a wearer for inflation by air from the wearer's lungs. Of course, if there is sufficient time to inflate the vest before the 25 wearer must take to the water, the vest compartments may be completely inflated through these tubes without operating the pressure medium container, so that the pressure medium may be reserved for a future more serious emergency, such as when the wearer is thrown into the water 30 without having time to inflate the vest, in which case a pull on the operating pull will effect rapid inflation of the vest.

The tubes 42 and 43 also serve to deflate the 40 vest when it has served its purpose, the deflation being effected by loosening the stoppers at the ends of the tubes.

At the time when the vest is deflated it is well to replace the empty pressure medium container 4 with a fully charged container. In order to accomplish this, all that is necessary is to unscrew the empty container from the coupling 5 and replace it by a charged container, as the container and its release means comprise a replaceable unit. Care should be taken, however, that the cam 28 has been returned to its normal position of engagement by the spring pressed catch button 36, so that it will not cause release 55 of the pressure medium during the replacement process.

In completion of the description of the life-vest, it should be noted that the leak-proof fittings 7 and 8 each comprise a flanged thimble 46 threaded internally and externally, the threaded portion being passed through an opening in one of the fabric walls of the life-vest. A soft rubber gasket 47, interposed between the flange of the thimble 46 and the fabric wall, is compressed into gas-tight relation with the flange and wall by means of a threaded ring 48 engaging the external threads of the thimble and bearing on a washer 49 which serves as a bearing plate for the threaded ring 48 permitting the latter to turn in a manner which would be impossible if the ring were in direct contact with the fabric wall of the vest. The assembly of the fitting also includes a sealing gasket 50 for insuring a gas-tight joint between the thimble 46 and the 70 75

end-piece 51 of the branch connection 10 (or 8), which end-piece engages the internal threads of the thimble 48.

From the foregoing description it will be seen that I have provided inflatable flotation devices which incorporate the objects set out at the beginning and which will be recognized to constitute a decided improvement over the prior devices of this character. It will also be seen that the principles of construction of the present invention are broadly applicable to various types of inflatable flotation devices; so that, while the invention has been described with reference to the accompanying drawings, I do not wish it to be limited save as defined in the appended claims.

I claim:

1. A fluid distributing system for distributing a fluid medium under pressure to a plurality of compartments comprising a body member provided with a chamber, a fluid inlet passage for said chamber, a plurality of fluid outlet passages for said chamber; a container of fluid medium under pressure of the type comprising a container proper having an outlet opening, a frangible disc normally sealing said outlet opening, disc rupturing means for rupturing said frangible disc to release the fluid medium, and means normally yieldingly retaining said disc rupturing means out of contact with said frangible disc; means to connect said container to said inlet passage so that the contents thereof may be discharged into said chamber, the arrangement being such that the fluid release means of said container may be operated from within the chamber of the body member through said inlet passage, a striking pin arranged axially within said inlet passage in such a position that it may be forced into operative engagement with said disc rupturing means; means for guiding said striking pin mounted within said inlet passage, said last named means being provided with an opening for permitting the passage of the fluid medium therethrough, a spindle journaled in a wall of the chambered body member at right angles to the axis of said striking pin and extending exteriorly and interiorly of said wall, packing means encompassing said spindle for preventing leakage of the fluid medium past the spindle, a cam mounted on said spindle within said chamber in a position to forcibly engage the striking pin when the spindle is rotated, said cam being formed with a depression on the periphery thereof adapted to be yieldingly engaged by locking means to normally maintain the cam out of forcible engagement with the striking pin, a spring pressed detent mounted within a wall of the chambered body member and adapted to yieldingly engage the depression in the cam to lock the same as aforesaid, means external to the chambered body member to effect rotation of the spindle to actuate the cam to engage the striking pin to effect release of the fluid medium from the container, and a check valve in each outlet passage from the chambered body member to prevent flow of the fluid medium from the several compartments back into the chambered body member and to prevent intercommunication of the compartments.

aforesaid, means external to the chambered body member to effect rotation of the spindle to actuate the cam to engage the striking pin to effect release of the fluid medium from the container, and a check valve in each outlet passage from the chambered body member to prevent flow of the fluid medium from the several compartments back into the chambered body member and to prevent intercommunication of the compartments.

2. A fluid distributing manifold for distributing a fluid medium under pressure to a plurality of compartments comprising a body member provided with a chamber, a fluid inlet passage for said chamber, a plurality of fluid outlet passages for said chamber, means to connect to said inlet passage the fluid release means of a container of fluid medium under pressure having fluid release means of the type operable by forcible engagement therewith of a striking element, the arrangement being such that the fluid release means may be operated by a thrust applied through said inlet passage and so that the contents of the container may be discharged into said chamber, a striking pin arranged axially within said inlet passage in such a position that it may be forced into operative engagement with the fluid release means of the container, means for guiding said striking pin mounted within said inlet passage, said last named means being provided with an opening for permitting the passage of the fluid medium therethrough, a spindle journaled in a wall of the chambered body member at right angles to the axis of said striking pin and extending exteriorly and interiorly of said wall, packing means encompassing said spindle for preventing leakage of the fluid medium past the spindle, a cam mounted on said spindle within said chamber in a position to forcibly engage the striking pin when the spindle is rotated, said cam being formed with a depression on the periphery thereof adapted to be yieldingly engaged by locking means to normally maintain the cam out of forcible engagement with the striking pin, a spring pressed detent mounted within a wall of the chambered body member and adapted to yieldingly engage the depression in the cam to lock the same as aforesaid, means external to the chambered body member to effect rotation of the spindle to actuate the cam to engage the striking pin to effect release of the fluid medium from the container, and a check valve in each outlet passage from the chambered body member to prevent flow of the fluid medium from the several compartments back into the chambered body member and to prevent intercommunication of the compartments.

DANIEL MAPES.

60.
